UNITED STATES PATENT OFFICE

106,090

DESIGN FOR A DRESS

David Rosenthal, New York, N. Y.

Application July 23, 1937, Serial No. 70,594

Term of patent 3½ years

To all whom it may concern:

Be it known that I, David Rosenthal, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The dress of my design comprises a pin tucked skirt in association with a yoked blouse section and is characterized by the coin-like ornaments down the blouse front and on the belt in combination with the dress as shown.

I claim:

The ornamental design for a dress, substantially as shown, and described.

DAVID ROSENTHAL.
